UNITED STATES PATENT OFFICE.

WILLIAM A. LURIE, OF CHICAGO, ILLINOIS.

DOOR-LOCK.

1,163,525.

Specification of Letters Patent. Patented Jan. 18, 1916.

Application filed March 10, 1915. Serial No. 13,325.

To all whom it may concern:

Be it known that I, WILLIAM A. LURIE, a citizen of the United States, and a resident of Chicago, in the county of Cook and State 5 of Illinois, have invented certain new and useful Improvements in Door-Locks, of which the following is a specification.

My invention relates to door locks and may be considered as an improvement over 10 the construction shown and described in my Patent No. 1,102,527, dated July 7, 1914, and in my application Serial No. 845,620, filed June 17, 1914.

The object of the invention is to reduce 15 the number of parts and to provide more simple and compact arrangement of the parts.

The invention is of that class in which 20 detent pawls are provided in the bolt head for preventing the bolt from being pried open. In the lock of my application referred to these pawls project beyond the bolt head when the bolt is in and must drag across the edges of the bolt outlet opening 25 particularly when the door is slammed. Such drag of course introduces friction and wear on the pawls and has the further disadvantage that outward movement of the bolt would be impeded.

Another important object of my invention 30 is therefore to provide means for keeping the pawls entirely within the bolt head during the time that the bolt is moving outwardly after the inward movement thereof 35 caused by closing the door by slamming.

The various features of my invention are clearly illustrated on the accompanying drawings in which—

Figure 1 is an elevational view of the lock 40 with the cover plate removed and with parts in section to more clearly show the construction and arrangement, Fig. 2 is a sectional view on plane 2—2, Fig. 1, Fig. 3 is an elevational view similar to Fig. 1 but showing 45 the bolt in its inner position, Fig. 4 is a sectional view on plane 4—4, Fig. 1, and Fig. 5 is a front view of the outer end of the bolt.

The lock mechanism is inclosed in a casing 50 having the face plate 11 provided with the bolt opening 12. The bolt shank 13 terminates in the head 14 having the tapered front surface 15, the bolt being adapted to travel longitudinally and being 55 guided by the walls surrounding the opening 12, and by the guide studs 16. The bolt

head is hollow and contains pawls 17 and 18 pivoted at their inner ends on pins 19 and 20 within the head 14. The outer ends of the pawls have laterally projecting detent 60 teeth *a* and *b* respectively, these teeth being adapted to pass through passageways *c* and *d* to the exterior of the head to project beyond the upper and lower sides thereof. The wall sections 21 and 22 limit the outward 65 swing of the pawls. On the bolt shank 13 is a spreader bar 23 which is longitudinally 70 slideable on said shank and is guided by means of screws 24 secured to the shank and extending through the longitudinal slot 25 75 in the bar. The front end of the bar cooperates with the pawls 17 and 18 and when the bolt is out and the bar is in its outer position its front end will spread the pawls apart to cause their teeth *a* and *b* to extend 80 through passageways *c* and *d* and beyond the sides of the bolt head as indicated in Fig. 1, whereas when the bar is in its inner position it will be released from the pawls and these pawls will be swung to be entirely 85 within the bolt head, as shown in Fig. 3, such swing being caused by springs 26 and 27 mounted on the bolt structure and engaging with the inner ends of the pawls as clearly indicated.

Extending through the lock casing is the bar 28 whose ends support door knobs. Within the lock casing is a hub 29 for receiving the polygonal door knob bar 28, this hub having upper and lower cam extensions 90 30 and 31. Below the hub the lower wall of the lock casing provides a pivot ridge 32 on which the lever 33 is pivoted, the lever having the notch 34 in its lower end receiving the pivot ridge. The lever has the 95 pocket 34 for receiving the hub and has the upper and lower cam points 35 and 36 at the edges of the pocket in position to be engaged by the cam arms 30 and 31 respectively on the hub. A lateral abutment projection 37 at the lower end of the lever 33 is engaged by a spring 38 anchored at its other end between the lugs 39 and 40 on the lock casing, this spring tending to hold the lever 33 in vertical position as indicated in 100 Fig. 1, in which position the cam points 35 and 36 are engaged by the cam arms 30 and 31 respectively. Referring to Figs. 1 and 3, when the knob is turned in clockwise direction cam arm 30 will engage with cam point 110 35 and will swing the lever to the right, and when the knob is turned in the opposite di-

rection cam arm 31 will engage the cam point 36 and will swing the lever in the same direction. Extending forwardly from the upper end of the lever 33 is a pin 41 which passes through a notch 42 at the upper end of a wing 43 extending upwardly from the bolt shank, the pin also extending through the notch 44 at the upper end of the wing 45 extending upwardly from the inner end of the spreader bar 23. The notch 42 is wider than the notch 44 and consequently when the knob is turned the spreader bar 23 will be shifted a distance before the bolt is shifted, this being for the purpose of first 15 effecting drawing in of the detent pawls before the bolt is drawn in upon turning of a door knob. In Fig. 1 the parts are in normal position, the pin 41 resting against the front ends of the notches 42 and 44 respectively, the bolt being out and the spreader bar at its front end wedging the pawls outwardly so that the teeth *a* and *b* abut against the face plate above and below the bolt opening 12. The bolt is thus locked 20 against inward movement by any implement inserted between the door and the jamb. However, when the knob is turned and lever 33 swung the spreader bar will be immediately shifted inwardly away from the pawls in order that springs 26 and 27 may 25 draw the pawls into the bolt head, and then as soon as the bolt reaches the inner end of the notch 42 the bolt will be drawn inwardly in order that the door may be opened. Upon 30 release of the knob the spring 38 will swing the lever 33 forwardly and the bolt will be shot outwardly and the spreader bar will again spread out the pawls into detaining 35 position in front of the face plate. In order 40 to allow closure of the door when it is swung toward closed position without turning of the knobs, a trigger 46 is pivoted within the bolt head in a plane at right angles to that of the pawls, the outer end *e* of the trigger extending normally beyond the surface 15 of the bolt and the finger *f* on the trigger extending in front of the spreader bar 23. A spring 47 secured at one 45 end to the bolt shank engages at its other end against the abutment end *g* of the trigger and tends to hold this trigger in its outer normal position. Whenever the door is closed the trigger will engage with the jamb plate and will be shifted into the bolt 50 head, and therefore, when the door is pushed shut without turning of the knobs, the trigger during its swing into the bolt head will shift the spreader bar inwardly to release its outer end from the detent pawls in 55 order that such detent pawls may swing entirely within the bolt head to permit inward movement of the bolt when the surface 15 reaches the jamb plate. When the door is closed the bolt will then be out with its head in the jamb and the trigger will be 60

locked into the head of the bolt by the outer end of the spreader 23 by virtue of its surface riding over the outer surface of the finger of the trigger 46.

As soon as the bolt is released after inward movement thereof, either by turning of a knob or by contact of the front slanting face of the bolt head with the jamb plate, the first part to move will be the spreader bar and the pawls will be spread 70 apart to project their detent teeth. This occurs before the bolt begins to move to its out position. Unless prevented the detent teeth would therefore have to drag across the edges of the bolt opening, and the friction would cause wear of the pawls, but the main disadvantage would be that this friction would impede or perhaps block the outward movement of the bolt. The outer ends of the pawl teeth have been rounded and the engagement of such rounded ends with the bolt opening edges has been depended upon to swing the teeth into the bolt head. Of course where the lock parts are kept well lubricated the pawls would readily be swung 80 into the bolt head and the friction of their front ends with the bolt opening edges would be negligible. However, locks are very seldom given much attention after 85 their first installation and the oil soon dries and the parts soon become gritty and roughened. Under such conditions the friction at the pawl pivots and of the front ends of the pawls against the opening edges might be sufficient to block the bolt against outward 90 movement. I therefore provide means for allowing the detent pawls to be withdrawn into the bolt head before the bolt itself is released and to prevent spreading thereof until the bolt is entirely out. 105

Pivoted to the up-standing lug 48 on the bolt shank 13 is the bell crank detent lever 49. The front end of this lever has the detent hook 50 for coöperating with the detent notch 51 in the upper edge of the releasing bar 23, a spring 52 secured to the bolt shank tending to hold the detent end 50 down. In the path of the upper end of the lever 49 is the tripping abutment 53 extending from the lock frame. The position 110 of this tripping abutment is such that just before the bolt reaches its outer position the upper end of lever 49 will strike the abutment and will swing the detent end 50 up, as indicated in Fig. 1. When the bolt 115 is out the detent notch 51 is a short distance in advance of the detent end 50 of the lever, but when the bolt is shifted inwardly the notch will come behind the detent end 50 and then as soon as the lever leaves the tripping abutment 53 the spring 52 will swing the end 50 down into the notch or against the releasing bar in advance of the notch. 120 Then when the bolt starts to move forwardly after an inward movement, the de 125

tent end 50 and notch 51 will coöperate to limit the forward movement of the spreader bar on the bolt, that is, the releasing bar will be stopped in its movement relative to the bolt just before such engagement with the pawls as would result in spreading apart of the pawls. Such locking is maintained until the bolt head is practically entirely out, and then the upper end of the lever 49 will strike the tripping abutment 53 and the lever will be swung to unlatch the spreader bar whereupon the bar is moved out of its full distance and the pawls will be spread to effect detent engagement of the teeth thereof with the lock face plate. Thus the shifting movement of the bolt is at no time impeded by the frictional engagement of the pawls with the face plate and complete upward movement of the bolt and efficient locking is at all times assured. Means are also provided whereby the bolt can be operated by a key inserted in a lock cylinder (not shown) which is supported in the pocket 54 provided in the lock wall. A bell crank lever 55 is pivoted at its elbow adjacent the cylinder opening and its lower end has the pin 56 extending through notches 57 and 58 in the bolt shank and spreader bar respectively, the notch 57 being wider than the notch 58 and the arrangement being precisely the same as the arrangement with reference to the pin 41 and the notches 42 and 44 at the inner end of the bolt where the bolt is controlled through turning of a door knob. Pivoted above the bell crank lever 55 is a lever 59 having an intermediate engaging point 60 for cooperating with the top of the lever 55 to effect swing thereof when the lever 59 is swung. The lever 59 has connection with the key cylinder (not shown) and upon turning of the key the lever 59 will be swung from the position shown in Fig. 1 to the position shown in Fig. 3, this movement effecting swing of the bell crank lever 55 and inward movement of the bolt mechanism. Upon release and withdrawal of the key the spring 38 will be the cause of all the parts returning to normal position. It may also be desirable to prevent the lock from being opened by means of the door knobs. To this end the hub 29 carries a forwardly extending wing 61 having the notch 62 at its front edge for receiving the end of detent bar 63 which at its inner end is guided in the lug 64 on the lock casing and at its outer end 65 is guided in the sleeve 66 in the face plate, this outer end forming a button. When the bar 63 is shifted inwardly it will engage in notch 62 and will lock the hub 29 and consequently the bar 28 and the door knobs against turning and opening of the door will thus be prevented. To release the bar 63 from the notch 62 another button member 67 is pro-

vided to be operable through sleeve 68 below the sleeve 66 in the face plate. This button member 67 is connected by a rocking lever 69 with the bar 63, the lever being pivoted at an intermediate point on the pin 70 extending from the lock casing. With this lever arrangement, the bar 63 will be shifted out to release the knob mechanism when the button member 67 is pushed in. A spring 71 extending from the bar 63 and coöperating with the top of lug 64 tends to lock the bar 63 in either its in or out position.

I do not of course desire to be limited to the exact structures, arrangements and operations shown and described, as modifications are no doubt possible which would still come within the scope of the invention.

I claim as follows:

1. In a door lock, the combination of a containing case having a face plate provided with a bolt opening, a bolt member having a head adapted to slide through said opening, detent pawls pivoted in said head and having detent teeth, means tending to swing said pawls to be entirely within said head, a spreader bar slidable on said bolt member, spring means acting on said bolt member and spreader bar and tending to force said members outwardly, means for causing outward movement of the spreader bar on the bolt member before outward movement of the bolt member by the spring means, said spreader bar being adapted during the latter part of its outward movement to coöperate with said pawls to spread them apart to carry their teeth beyond the sides of the bolt head, a detent member for checking the forward movement of the spreader bar on the bolt member before said spreader bar reaches full outer position whereby to prevent coöperation of said bar with said pawls and to allow the bolt head to reach its outer position while the pawls are still within the head, and means for effecting release of the detent member after the bolt head has reached its outer position whereby to then allow the spreader bar to coöperate with the detent pawls to spread said pawls to carry their teeth into detent position beyond the sides of said bolt head.

2. In a door lock, the combination of a containing casing having a face plate provided with a bolt opening, a bolt member slidable within said casing and having a head adapted to pass through said opening, detent pawls pivoted within said head and having detent teeth at their outer ends, springs on said bolt member tending to swing said pawls to carry their teeth beyond the upper and lower sides of the bolt head whereby when said bolt member is out said pawls will prevent inward movement thereof, a spreader bar slidable on said bolt member and adapted in its outer position thereon

for engagement with said pawls to spread said pawls to carry their teeth outwardly, shifting mechanism for said bolt member and spreader bar adapted when operable in outward or rearward direction to cause shifting of the spreader bar in advance of shifting of the bolt member whereby during operation rearwardly of the shifting mechanism said spreader bar will first withdraw from the pawls before the bolt is shifted rearwardly and whereby during outward operation of the shifting means said spreader bar will tend to spread the pawls apart before outward shift of the bolt, and 10 detent means for coöperating with the spreader bar during outward movement of the bolt member for preventing outward movement of the bar on the member to thereby prevent spreading of the pawls by said bar while the bolt head is passing through said opening, and means for releasing the detent means after the bolt member is in its outer position whereby to allow forward movement of said spreader bar and spreading 20 apart of the pawls.

3. In a lock, the combination of a containing casing having a face plate provided with a bolt opening, a bolt member slideable within said casing and having a head 30 adapted to pass through said opening, pawls pivoted in said head and having detent teeth at their outer ends, springs on the bolt member acting on said pawls to swing them to be entirely within said head, a spreader bar 35 slideable on said bolt member, means tending to shift said bar forwardly on said bolt member and into wedging engagement with said pawls to spread said pawls outwardly to carry their teeth beyond the upper and 40 lower sides of the bolt head, actuating means for shifting said bolt member inwardly, a connection between said actuating means and said spreader bar for effecting rearward movement of said bar on said bolt member 45 before inward actuation of said bolt member whereby said pawls are first released and allowed to swing into the bolt head before inward movement of the bolt member, spring means adapted upon release of said actuating 50 means to restore same to normal position, said spreader bar tending upon such restoring movement to shift forwardly on the bolt member to spread the pawls apart before forward movement of the bolt member, 55 and detent mechanism for preventing such forward movement of the bar until the bolt member has substantially reached its outer position whereby the said pawls will be retained within the bolt head until the bolt 60 head reaches its outermost position.

4. In a lock, the combination of a containing casing having a front wall provided with a bolt opening, a bolt reciprocable within said casing and having a head adapted to pass through said opening, detent pawls

pivoted within said head and having detent teeth at their outer ends adapted upon spreading apart of the pawls to extend beyond the upper and lower sides of the bolt head to block inward movement of the bolt head, means on said bolt member tending to swing the pawls to be within the head, a bar slideable on said bolt member and adapted when in its outer position to engage at its front end between said pawls to spread them to carry their teeth beyond the sides of the bolt head, shifting mechanism for controlling the outward and rearward shift of the bolt and bar and adapted during shift in either direction to first cause primary shift 70 of the bar whereby during inward shifting said bar will first be released from the pawls before the bolt is shifted inwardly and whereby during the outward shift said bar will tend to engage with the pawls before 75 outward shift of the bolt, means for locking said bar to the bolt member away from said pawls during outward movement of the bolt member to prevent swinging apart of the pawls during such outward movement, and means for releasing the bar after the bolt member has been shifted outwardly.

5. In a lock, the combination of a containing casing having a front wall provided with a bolt opening, a bolt reciprocable within said casing and having a head adapted to pass through said opening, detent pawls pivoted within said head and having detent teeth at their outer ends adapted upon spreading apart of the pawls to extend beyond the upper and lower sides of the bolt head to block inward movement of the bolt head, means on said bolt member tending to swing the pawls to be within the head, a bar slideable on said bolt member and adapted when in its outer position to engage at its front end between said pawls to spread them to carry their teeth beyond the sides of the bolt head, shifting mechanism for controlling the outward and rearward shift of the bolt and bar 95 and adapted during shift in either direction to first cause primary shift of the bar whereby during inward shifting said bar will first be released from the pawls before the bolt is shifted inwardly and whereby during the outward shift said bar will tend to engage with the pawls before outward shift of the bolt, a latch for locking the bar against outward movement on the bolt member to prevent said bar from spreading the 105 pawls during outward movement of the bolt member, and means for tripping said latch during the latter part of the outward movement of said bolt member whereby said bar may then coöperate with the pawls to spread them apart after the bolt head has reached its outer position.

6. In a lock, the combination of a containing casing having a front wall provided with a bolt opening, a bolt reciprocable with- 110

in said casing and having a head adapted to pass through said opening, detent pawls pivoted within said head and having detent teeth at their outer ends adapted upon 5 spreading apart of the pawls to extend beyond the upper and lower sides of the bolt head to block the inward movement of the bolt head, means on said bolt member tending to swing the pawls to be within the head, 10 a bar slideable on said bolt member and adapted to engage at its front end between said pawls to spread them to carry their teeth beyond the sides of the bolt head, shifting mechanism for controlling the outward 15 and rearward shift of the bolt and bar and adapted during shift in either direction to first cause primary shift of the bar whereby during inward shifting said bar will first be released from the pawls before the bolt is 20 shifted inwardly and whereby during the outward shift said bar will tend to engage with the pawls before outward shift of the bolt, a latch member pivoted on said bolt member and adapted for latching engagement 25 with said bar to prevent outward movement thereof on the bolt member during outward movement of the bolt member whereby to prevent spreading apart of the pawls by said bar during outward movement of the bolt member, and means for releasing the latch member from said bar after 30 said bolt member has practically reached its outer position whereby said bar may then effect spreading of the pawls.

7. In a lock, the combination of a containing casing having a front wall provided with a bolt opening, a bolt reciprocable with-

in said casing and having a head adapted to pass through said opening, detent pawls pivoted within said head and having detent teeth at their outer ends adapted upon 40 spreading apart of the pawls to extend beyond the upper and lower sides of the bolt head to block inward movement of the bolt head, means on said bolt member tending to 45 swing the pawls to be within the head, a bar slideable on said bolt member and adapted to engage at its front end between said pawls to spread them to carry their teeth beyond 50 the sides of the bolt head, shifting mechanism for controlling the outward and rearward shift of the bolt and bar and adapted during shift in either direction to first cause primary shift of the bar whereby during 55 inward shifting said bar will first be released from the pawls before the bolt is shifted inwardly and whereby during the outward shift said bar will tend to engage with the pawls before outward shift of the bolt, a bell crank latch lever pivoted at its 60 elbow to said bolt member, means for holding said latch member in latching engagement with said bar to prevent outward movement of the bar on the bolt member when said bolt member is shifted outwardly, 65 and a tripping abutment in the path of said latch lever for effecting release thereof from the bar after the bolt member has practically reached its outermost position whereupon said bar may then effect spreading 70 apart of said pawls.

In witness whereof I hereunto subscribe my name this 3rd day of March, A. D., 1915.

WILLIAM A. LURIE.
